SWIVEL JOINT

Stig H. Bjarne Zachariassen, Stockholm, Sweden,
assignor to Aktiebolaget Separator, Stockholm,
Sweden, a corporation of Sweden

Application February 4, 1948, Serial No. 6,309
In Sweden March 3, 1947

12 Claims. (Cl. 285—97.1)

1 This invention relates to a tightening device in centrifugal separators, intended to be used between the bowl and a stationary inlet or outlet pipe, so as to obtain a communication between these parts in which only a relatively insignificant leakage of liquid is likely to occur.

It has previously been suggested to use a tightening device for the same purpose, having a tightening ring with a cylindrical, spherical or plane tightening surface supported by a corrugated tube and contacting with a tightening disc fixed to the rotating separator bowl. The use of corrugated tubes in constructions of this kind is, however, objectionable in some cases, because the tightening device cannot then be used for a corrosive liquid, for example sulphuric acid, as this would eat through the thin wall of the corrugated tube. There are other instances in which corrugated tubes may be unsuitable, for example, where the centrifuge inlet or outlet contains high pressures which a corrugated tube cannot stand.

The present invention, therefore, is directed to the provision of an improved tightening device by which the above-mentioned inconveniences are overcome. In the new device, the tightening ring, or a holder or the like connected thereto, is arranged to swing or otherwise move relative to a stationary part, and a packing ring is provided between the tightening ring or the holder and the stationary part.

For a better understanding of the invention, reference may be had to the accompanying drawings, in which

Fig. 1 is a side elevational view, partly in section, of the upper part of a separator made in accordance with the invention;

Fig. 2 is a vertical sectional view of the upper part of a modified form of the separator, and

Fig. 3 is a view similar to Fig. 2 but showing still another form of the separator.

In the embodiment according to Fig. 1, which shows a separator provided with a liquid seal in the outlet, a stationary outlet tube 1 is formed in the cover 13 of the frame, through which outlet the centrifuged liquid is discharged from a separator bowl 2. A tightening disc 3 is secured to the upper part of bowl 2 by a nut 4. The tightening disc 3 is engaged by a tightening ring 5 supported by a holder 6, which is guided in the outlet tube 1. There is a clearance between the periphery of holder 6 and the outlet tube 1, this clearance being such that the play between the outlet tube 1 and the holder 6 is just sufficient to permit the holder 6 to swing some-

2 what. According to the lateral deviation and the angular movement of the separator bowl 2 incident to its rotation, which cause tilting of the bowl and therefore its tightening disc 3, the tightening surface of the ring 5 may thus assume such positions that it remains parallel with the tightening surface of the disc 3, with which it cooperates. Above holder 6 is a packing ring 7 of, for example, rubber which surrounds the tube 1 and is kept pressed on the holder 6 by a disc 8 acted upon by a spiral spring 9. The latter at the same time exerts a pressure on holder 6 great enough always to insure contact between the tightening ring 5 and the tightening disc 3, even if the tightening surfaces of these parts should become somewhat worn.

In its free condition, the inner diameter of packing ring 7 is somewhat smaller than the outer diameter of outlet tube 1, which insures a satisfactory tight joint between the cylindrical surfaces of these parts, since the packing ring 7 must be expanded to force it on the outlet tube 1.

In addition to the pressure exerted by spiral spring 9, which is transmitted to tightening ring

25 5 via packing ring 7 and holder 6, the pressure of a sealing liquid surrounding outlet tube 1 (as will be described presently) also contributes to an increased tightening effect between tightening ring 5 and tightening disc 3, since the outer diameter of outlet tube 1 is smaller than the average diameter of the tightening surface of ring 5, whereby the latter ring is pressed against the tightening disc 3. With this arrangement, even with high liquid pressures at the bowl outlet and in spite of the movements performed by the bowl, the only leakage which can occur will be in the form of a thin film of liquid between the tightening ring 5 and the tightening disc 3.

30 A packing ring 10 arranged in a holder 11, also contacts the disc 3. The ring 10 and holder 11 surround the lower part of outlet tube 1 in spaced relation thereto and are connected with the cover 13 of the frame by means of a corrugated tube or bellows 12. The parts thus define a space 14 to which the sealing liquid is fed through a channel 15 in the cover 13. In the space 14 is a tube 16 threaded to the top of cover 13, from which it extends downwardly between the bellows 12 and the outlet tube 1. At its lower end, the tube 16 is provided with an inwardly projecting flange or stop 17 which limits the downward movement of the holder 6. It will be understood that the sealing liquid is supplied from inlet 15 through the space between bellows 12 and tube 16, around the bottom of

tube 16, through the space between holder 6 and tube 16, and into the annular chamber between the tubes 1 and 16.

In the embodiment illustrated in Fig. 2, the invention is applied to the outlet from a separator without sealing liquid, the pressure on the inside of the seal being higher than on its outside. In the top of the separator bowl 2a is screwed a holder 18 in which is located a tightening disc 3a which thus rotates with the separator bowl, as in the Fig. 1 embodiment. A tightening ring 5a, supported by a holder 6a, contacts the tightening disc 3a. On its outer side, the holder 6a is guided by the inner cylindrical surface of a sleeve 19, which in turn is screwed into a ring 20 threaded in the cover 13a of the separator frame. The cylindrical guiding surface between holder 6a and sleeve 19 is short and so formed as to allow movement of holder 6a relative to the axis of the separator.

As in the embodiment shown in Fig. 1, a packing ring 7a of rubber is provided above the holder 6a. Ring 7a is in this case so dimensioned that, upon being placed in the sleeve 19, it exerts an outward expansive force against the inner cylindrical guiding surface of sleeve 19. Above packing ring 7a is a disc 8a with which a spiral spring 9a contacts, the purpose of which is to press the tightening ring 5a against tightening disc 3a in the same manner as in the embodiment shown in Fig. 1. The packing ring 7a is, however, provided with conical top and bottom surfaces 21 so that, under the pressure of spring 9a, the packing ring is forced towards the clearance between holder 6a and the cylindrical inside of sleeve 19.

In the arrangement shown in Fig. 3, the packing ring 7b consists of a rubber ring of U-shaped section and is placed in a groove in the inner surface of holder 6b. The packing ring 7b may, however, also be made of a metal. Between holder 6b and outlet tube 1 there is also a packing ring 21 of L-shaped section and made of thin sheet material, the ring 21 being seated on top of the holder 6b. The fit of the cylindrical part 21 is preferably such that a good tight joint is obtained between it and the outlet tube 1. In this construction, the outer holder 11b presses the outer packing ring 10b on the disc 3 by means of a spring 22. Into the cover 13b of the frame a sleeve 23 is threaded, which is provided with an inwardly projecting flange 24 with which a packing ring 25 contacts, the latter being fixed on the holder 11b. This packing ring is compressed by a ring 27, actuated by a spring 26, whereby a tight joint is obtained between the sleeve 23 and the packing ring 25 as well as between the latter and the holder 11b so that the space 14b, intended for the sealing liquid, is closed without using a corrugated tube or bellows.

It will be apparent that in the illustrated forms of the invention, the centrifuged liquid from the separator bowl is discharged through the stationary tube 1 (Figs. 1 and 3) or 19 (Fig. 2), and the passage between the bowl outlet and the stationary tube is so arranged as to prevent any substantial leakage of the outflowing liquid and yet allow the usual relative movement between the rotating and stationary parts due to vibrations and any unbalanced condition of the bowl. More particularly, the tightening member 3 can move laterally relative to the tightening ring 5 which it contacts, although this movement occurs while the parts are pressed

together by the spring 9 so that there will be no appreciable leakage between the sealing surfaces. The packing ring 7 (21 in Fig. 3), which is also compressed by the spring 9, prevents leakage between the tightening ring 5 and the stationary outlet tube, and at the same time, because of its flexible nature, it allows some relative movement between the holder 6 and the stationary outlet tube. The spring 9 serves to accommodate vertical movements of the bowl relative to the frame cover 13 and also to maintain a constant pressure between the sealing surfaces of the parts 3 and 5 in spite of wearing of these parts. In the Fig. 1 and Fig. 3 embodiments, the outer tightening ring 10 is also adapted to slide on the tightening disc 3, against which it is pressed, to accommodate lateral movements of the bowl. The tightening rings 10, of course, serve to retain the sealing liquid which exerts an additional pressure on the relatively movable sealing surfaces.

While the invention has been specifically described and illustrated in connection with an outlet of a centrifuge, it will be understood that it may be applied with equal facility and with the same advantages to the centrifuge inlet. Also, the construction may vary in its details, within the scope of the appended claims.

I claim:

1. In a centrifuge having a centrifugal bowl and a stationary pipe communicating with the interior of the bowl, the combination of a tightening disc rotatable with the bowl and having an opening through which communication is afforded between the bowl and said pipe, the disc moving radially and tilting with the bowl relative to the stationary pipe incident to the bowl rotation, a tightening ring engaging said disc and surrounding said opening, said disc being movable relative to the tightening ring while maintaining a sealing contact therewith, and a packing ring of rubber-like material interposed between the tightening ring and the stationary pipe, said packing ring and tightening ring at least partly defining a passage communicating between the bowl and said pipe and acting to seal against leakage from said passage, there being a clearance between said tightening ring and the stationary pipe to allow the tightening ring to undergo axial and tilting movements relative to said pipe, whereby said tightening ring is adapted to assume relative to said disc at all times a position for maintaining a tight joint therewith.

2. A combination according to claim 1, comprising also a spring acting upon the packing ring to press the same against the stationary pipe and also to press the tightening ring against said disc.

3. A combination according to claim 1, in which the packing ring in its unassembled condition is of different size than said stationary pipe which it engages, whereby the packing ring exerts a pressure against said pipe to form a tight joint therewith by the elasticity of the packing ring.

4. A combination according to claim 1, in which the packing ring is U-shaped in cross-section.

5. A combination according to claim 1 in which the packing ring is L-shaped in cross-section.

6. A combination according to claim 1, comprising also a holder for the tightening ring and interposed between the tightening ring and said packing ring.

7. A combination according to claim 1, comprising also a second tightening ring engaging

the tightening disc and surrounding the first tightening ring, and means forming a movable joint between said second tightening ring and said pipe and partly defining a space for a sealing liquid outside said passage.

8. A combination according to claim 1, comprising also a second tightening ring engaging the tightening disc and surrounding the first tightening ring, and a bellows forming a movable joint between said second tightening ring and said pipe and partly defining a space for a sealing liquid outside said passage.

9. A combination according to claim 1, comprising also a second tightening ring engaging the tightening disc and surrounding the first tightening ring, and means including a second packing ring of rubber-like material forming a movable joint between said second tightening ring and said pipe and partly defining a space for a sealing liquid outside said passage.

10. A combination according to claim 1, in which said packing ring is stretched over the stationary pipe.

5
15
10

11. A combination according to claim 1, in which said packing ring is retained in a circumferentially compressed condition in the stationary pipe.

12. A combination according to claim 1, comprising also a holder for the tightening ring and interposed between the tightening ring and the packing ring, the holder being urged toward the disc to press the tightening ring against the disc, and a stop engageable by the holder to limit movement thereof toward the disc.
